JOSEPH CARDINAL, OF BROOKLYN, NEW YORK.

BOILER PLUG.

Application filed August 27, 1924. Serial No. 734,527.

To all whom it may concern:

Be it known that I, JOSEPH CARDINAL, a citizen of the United States, and a resident of the city of New York, borough of Brooklyn, in the county of Kings and State of New York, have invented a new and Improved Boiler Plug, of which the following is a full, clear, and exact description.

The present invention relates to new and useful improvements in steam boiler appliances and it pertains more particularly to a plug for use in connection with boiler heads.

It is one of the primary objects of the invention to provide a plug for boiler heads which may be readily attached and removed from the head.

It is a further object of the invention to provide a plug for boilers which is locked against rotary movement during the operation of tightening or loosening the securing means thereof.

It is a further object of the invention to construct a boiler plug in such a manner that the same may be retained in position in the boiler head during the operation of placing the plug.

With the above specific commercially desirable possibilities in view, I have devised novel features including certain combinations and elements which are capable of use in specifically different relations or in connection with cooperating parts specifically different from those set forth herein.

My invention will be more fully understood in connection with the above and other objects in view, reference being had to the accompanying drawings, in which—

Figure 1 is a view in elevation of a section of a boiler head showing a plurality of plugs constructed in accordance with the present invention in position therein;

Fig. 2 is a detail sectional view taken on the line 2—2 of Fig. 1;

Fig. 3 is a detail sectional view taken on the line 3—3 of Fig. 1;

Fig. 4 is a perspective view of the plug removed from the head, and

Fig. 5 is a detail perspective view of one of the elements used in connection with the plug.

Referring to the drawings by reference numerals, 10 designates the boiler head, and 11 designates one of a plurality of openings in such head. The reference character A designates the plug, which plug has a head 12 and a reduced shoulder 13 from which

projects a stem 14, the outer end of which is screw-threaded as shown at 15. The shoulder 13 is of substantially the same diameter as the hole to be closed, and the head 12 of the plug engages the inner face of the boiler head 10, as shown in Fig. 2. A gasket 16 is employed between the head 12 of the plug and the boiler head 10, but this gasket may, if desired, be eliminated without departing from the spirit of the invention.

As more clearly shown in Fig. 4, the stem 14 of the plug A is provided intermediate of its ends with a portion 18 rectangular in cross section, and having two oppositely disposed flat faces 19. The thickness of this rectangular section is substantially equal to the diameter dimension of the stem 14, as shown, and in use this rectangular portion 18 is adapted to occupy a position to the rear 75 of the boiler head 10, as shown in Fig. 3.

The reference character B designates a key and such key is substantially U-shape in cross sectional form. The side walls 20 of the key are provided with a projecting portion 21, which is adapted to embrace the flat faces 19 of the rectangular portion 18 of the plug. This key B has an opening 22 which is adapted to receive the stem 14 to allow the key B to be passed over the stem with the projecting portions 21 of the key occupying a position within the opening 11 to be closed.

The reference numeral 25 designates a washer, which is adapted to pass on to the stem 14 of the plug A after the key B has 90 been positioned thereon, and 26 designates a nut which is adapted to pull the plug to position.

The device operates in the following manner: To secure the plug in the opening the 95 stem 14 is passed through the opening from the rear in the ordinary manner. The gasket owing to the shoulder 13 is retained in position and prevented from slipping with respect to the plug, thus assuring that the 100 gasket is always properly positioned with respect to the plug and opening. If, now, a suitable tool be inserted in the space between the defining edge of the opening 11 and the inner edge designated by the reference numeral 30 of the rectangular portion 18 of the same, the plug may be securely retained in position during the emplacing of the key B. When the key B is placed in position it engages the boiler head 10, as shown at 31 in 110 Fig. 3, after which the washer 25 and the nut 26 are positioned upon the threaded end

of the stem 14 and the nut is tightened to pull the plug to place.

In ordinary plug construction after the plugs have been in use in the boiler, owing to corrosion and other causes, the nuts used to secure the plugs in place "freeze" or stick, and when it is desired to remove the plug the nut cannot be loosened for this reason and great difficulty is experienced in removing, renewing, or replacing the plug. By referring to the construction set forth in the present application, it will be noted that the opening 22 in the key B is nearer one end of the key than the other, and this provides 15 a projecting section of the key, which according to the present invention is of sufficient length to overlap a portion of the next adjacent plug.

By this construction it is apparent that the 20 nut 26 may be either tightened or loosened since the plug is prevented from turning by engagement of the key with a portion of the adjacent plug since the key receives the rectangular portion 18 of the stem of the plug. 25 When the nut 26 is being tightened the longer end of the key will engage the adjacent plug on the right of the one being tightened. If, however, it is desired to remove the nut should the stem be stuck, the plug will rotate 30 to the left until the extended end of the key engages the extended end of the adjacent key on the left and thus prevent further turning of the plugs and effect a loosening of the nut.

35 While I fully show, describe, and have pointed out in the appended claims certain novel features of construction, arrangement and operation which characterize my invention, it will be understood by those skilled in 40 the art that I do not confine myself to all the precise details of construction herein set forth, and that various omissions, substitutions and changes in the forms, proportions, sizes and details of the device, and of the 45 materials used and of its operation, may be made without departing from the spirit of the invention or exceeding the scope of the appended claims.

What is claimed is:

50 1. A plug for use in boiler heads having a plurality of adjacent openings to be closed, said plug comprising a body portion adapted to be received in its respective opening, a stem projecting from said body portion, 55 and means associated with each stem and adapted for engagement with the said means on a plug carried in an adjacent opening to prevent turning of the plug within the opening during the setting or removal of the 60 plug.

2. A plug for boiler head openings comprising a head, a reduced portion on said head adapted to be received within the opening to be closed, a stem projecting from said 65 head through the opening and having a

threaded outer end, a rectangular portion on the stem disposed beyond the outer surface of the boiler head when the plug is seated, a key comprising a member of substantially U-shape in cross section having an opening 70 in its bight portion through which the outer end of the stem projects, said key embracing the rectangular portion between its side walls to prevent relative turning movement of the plug and stem with respect to the 75 key, a nut adapted for engagement with the end of said stem for effecting relative axial movement of the plug and stem with respect to the boiler head, the side walls of the key being of such length as to enable engagement 80 between said key and the key of the plug closing the adjacent opening whereby the keys of adjacent plugs coact with each other to prevent turning of the plug within the opening during the setting and removal 85 of the plug.

3. In combination with a boiler head, a plurality of plugs adapted to close the openings in said head, and means associated with each of said plugs and adapted to overlap 90 and have engagement with the means on an adjacent plug to prevent turning of the plug in the boiler head.

4. A plug for boiler head openings comprising a head, a reduced portion on said 95 head adapted to be received within the opening to be closed, a stem projecting from said head through the opening and having a threaded outer end, a rectangular portion on the stem disposed beyond the outer surface 100 of the boiler head when the plug is seated, diametrically projecting lugs from said rectangular portion, a key comprising a member of substantially U-shape in cross section having an opening in its bight portion 105 through which the outer end of the stem projects, said key embracing the rectangular portion between its side walls to prevent relative turning movement of the plug and stem with respect to the key, a nut adapted 110 for engagement with the end of said stem for effecting relative axial movement of the plug and stem with respect to the boiler head, the side walls of the key being of such length as to enable engagement between said 115 key and the key of the plug closing the adjacent opening whereby the keys of adjacent plugs coact with each other to prevent turning of the plug within the opening during the setting and removal of the plug, the said lugs constituting means behind which the end of a tool fulcrumed on the defining edge of the opening is adapted to be engaged for retaining the plug in seated position within 120 the opening during the application and removal of the nut and key.

5. The combination with a boiler head having a plurality of openings, of plugs adapted to close each of said openings, means associated with each of said plugs 125

adapted to overlap and engage with the means on an adjacent plug to prevent turning of the plug in the boiler head and means formed on each plug adapted to be engaged by a tool fulcrumed on the defining edge of the openings for retaining the plug in place during the application and removal of said first mentioned means.

6. A closure plug for use in boiler heads which are provided with a plurality of adjacent openings to be closed, in which said plug comprises a head adapted to fit within the opening, an annular enlarged flange on the head for engagement with the material defining the edge of the opening, a stem projecting from said head having a rectangular portion intermediate its ends of a width equal to the diameter of the stem and of a length to provide diametrically projecting lugs from the periphery of the stem

and a key comprising a member of substantially U-shape in cross section provided with a stem receiving opening in its bight portion, the side walls of said key being spaced apart a distance equal to the minor width 25 of the rectangular portion for snugly embracing said rectangular portion, means engaging the end of the stem to effect relative axial movement of the plug and stem with respect to the key and boiler head openings 30 for locking the key and plug in place, the edges of the side walls of the key engaging the boiler head, the said diametrically disposed projecting lugs of the rectangular portion defining a means with which a tool 35 fulcrumed on the edge of the opening is adapted to engage for retaining the plug in position within the opening during the application and removal of the key.

JOSEPH CARDINAL.
